[57] CLAIM

The ornamental design for a combined container/bottle and cosmetic wand applicators or the like, as shown and described.

DESCRIPTION

FIG. 1 is an exploded front elevational view of a combined container/bottle and cosmetic wand applicators or the like showing our new design. Its rear view being a mirror image;

FIG. 2 is another front elevational view with applicator caps on. Its rear view being a mirror image; FIG. 3 is a side elevational view of FIG. 2, its opposite side being the same;

FIG. 4 is a partially exploded side elevational view showing a second embodiment of our new design wherein the applicator caps have been modified;

FIG. 5 is a top plan view of FIG. 1;

FIG. 6 is a bottom plan view thereof;

FIG. 7 is an exploded front elevational view of a combined container/bottle and cosmetic wand applicators or the like showing a third embodiment of our new design; its rear view being a mirror image;

FIG. 8 is a front elevational view with applicator caps on. Its rear view being a mirror image;

FIG. 9 is a side elevational view of FIG. 8, its opposite side being the same;

FIG. 10 is a partially exploded side elevational view showing a fourth embodiment of our new design wherein the applicator caps have been modified;

FIG. 11 is a top plan view of FIG. 7;

FIG. 12 is a bottom plan view thereof;

FIG. 13 is an exploded front elevational view of a combined container/bottle and cosmetic wand applicators or the like showing a fifth embodiment of our new design;

FIG. 14 is a front elevational view with caps on. Its rear view being a mirror image;

FIG. 15 is a side elevational view of FIG. 14. Its opposite side being the same;

FIG. 16 is a partially exploded side elevational view showing a sixth embodiment of our new design wherein the applicator caps have been modified;

FIG. 17 is a top plan view of FIG. 13;

FIG. 18 is a bottom plan view thereof;

FIG. 19 is an exploded front elevational view of a combined container/bottle and cosmetic wand applicators or the like showing a seventh embodiment of our new design. Its rear view being a mirror image;

FIG. 20 is a front elevational view with applicator caps on. Its rear view being a mirror image;

FIG. 21 is a side elevational view of FIG. 20. Its opposite side being the same;

FIG. 22 is a partially exploded side elevational view showing an eighth embodiment of our new design wherein the applicator caps have been modified;

FIG. 23 is a top plan view of FIG. 19;
FIG. 24 is a bottom plan view thereof;
FIG. 25 is an exploded front elevational view of a combined container/bottle and cosmetic wand applicators or the like showing a ninth embodiment of our new design. Its rear view being a mirror image;

FIG. 26 is a front elevational view with applicator caps on. Its rear view being a mirror image;
FIG. 27 is a side elevational view of FIG. 26, its opposite side being the same;
FIG. 28 is a partially exploded side elevational view showing a tenth embodiment of our new design wherein the applicator caps have been modified;
FIG. 29 is a top plan view of FIG. 25; and
FIG. 30 is a bottom plan view thereof.
